US0D1069769S

(12) **United States Design Patent** (10) Patent No.: **US D1,069,769 S**
(45) Date of Patent: ** Apr. 8, 2025

(54) **OMNIDIRECTIONAL MICROPHONE**

(71) Applicants: **GUANGZHOU SHIYUAN ELECTRONICS CO., LTD.**,
Guangdong (CN); **GUANGZHOU SHIKUN ELECTRONICS CO. LTD.**,
Guangdong (CN)

(72) Inventor: **Jie Su**, Guangdong (CN)

(73) Assignees: **GUANGZHOU SHIYUAN ELECTRONICS CO., LTD.**,
Guangdong (CN); **GUANGZHOU Shikun ELECTRONICS CO. LTD.**,
Guangdong (CN)

(**) Term: **15 Years**

(21) Appl. No.: **29/910,175**

(22) Filed: **Aug. 16, 2023**

(30) **Foreign Application Priority Data**

Feb. 16, 2023 (CN) 202330054132.2

(57) **CLAIM**

The ornamental design for an omnidirectional microphone as shown and described.

DESCRIPTION

FIG. 1 is a front view of an omnidirectional microphone in accordance with the present invention;

FIG. 2 is a rear view of the omnidirectional microphone in FIG. 1;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is a second perspective view thereof.

1 Claim, 8 Drawing Sheets
